UNITED STATES PATENT OFFICE.

DON CARLOS TRAVIS, OF KENOSHA, WISCONSIN, ASSIGNOR TO SIMMONS COMPANY, OF KENOSHA, WISCONSIN, A CORPORATION OF DELAWARE.

BED-SPRING.

1,288,297.

Specification of Letters Patent. Patented Dec. 17, 1918.

Application filed January 20, 1917. Serial No. 143,447.

To all whom it may concern:

Be it known that I, DON CARLOS TRAVIS, a citizen of the United States, residing at Kenosha, in the county of Kenosha and 5 State of Wisconsin, have invented certain new and useful Improvements in Bed-Springs, of which the following is a specification.

The principal objects of the invention are: 10 to provide an improved bed spring which will be free from creaking or other objectionable noises, due to movement of the occupant; to provide a bed spring so organized that sag of the spring is substantially 15 confined to the weight-supporting area and does not cause tilting or distortion of the remaining portion of the spring, for instance, when the bed is occupied by two persons of different weights; to provide a 20 bed spring of the class described having at all times a substantially flat smooth surface free from projecting parts liable to injure the mattress or other bedding; to provide a neat, efficient, and practical bed spring 25 which shall be relatively simple in design, and economical to manufacture, and, in general, to provide an improved bed spring of the character referred to.

In the drawings, which illustrate a preferred embodiment of my invention—

Figure 1 is a top plan view of a full sized bed spring having my improvements;

Fig. 2 is a section taken on the line 2—2 of Fig. 1; and

Fig. 3 is a section taken on the line 3—3 of Fig. 1.

In the drawings, 10 represents a pair of longitudinal strut members spaced from the bottom of the spring proper and carrying 40 at their opposite ends cast bracket members 11. The ends of the strut members 10 rest upon the bedstead frame, and to the upper ends of the bracket members 11 there is secured, by bolts, rivets, or other suitable 45 means, a pair of opposed cross members 12, which, in the present instance, take the form of angle irons, as shown clearly in Fig. 2, the spring proper being stretched between the terminal cross members 12.

50 The longitudinal sides of the spring proper consist of relatively wide and laterally rigid but vertically flexible metallic straps or side bars 13, the ends of which are resiliently secured to the cross members 55 12 by means of pairs of helical springs 14

normally under a considerable tension, so that the side bars 13 will not sag unduly when the bed is occupied. Between the side bars 13 the surface of the bed spring is composed of a series of spaced apart, thin 60 metallic slats 15 which are vertically flexible but have a considerable amount of transverse rigidity so that they will remain substantially straight, even when subjected to considerable lateral pull. Each of the slat 65 members 15 is connected at each of its ends to the cross members 12 by means of a helical spring 16 normally under considerable tension.

In order to prevent lateral and vertical 70 separation of the adjacent slats 15, constituting the surface of the bed spring, they are connected together by means of parallel transverse rows of connecting members 17, 75 three rows of the said members, ordinarily being sufficient for a bed spring of the usual length. These connecting members 17 constitute an important feature of my invention, and preferably comprise a series of individual helicals, each end 18 of each 80 helical passing through an aperture 19 in the adjacent slat member 15. The end helicals of each transverse row are connected to the side bars 13 of the spring, and the normal length of each helical, together with the 85 spacing of the holes 19 in the slat members, is such that it is necessary to impart a considerable amount of tension to the helicals in order to connect the row between the side bars 13. As has been previously stated, the 90 side bars 13 are comparatively wide and laterally stiff, so that there is no appreciable bowing under the tension of the rows of helicals, even when the bed is fully loaded.

The advantages of my construction are 95 quite marked when compared with a spring having loosely articulated members for connecting the various parts of the spring together. With my spring, there is practically no tendency for the slats to tip or 100 twist, for the reason that the intermediate helicals 17, being normally under tension, effectually prevent such twisting tendency. Also, all of the parts of the spring being 105 normally subjected to tension, there is no tendency for the parts to slip, rattle, or change position when the load is applied to or removed from the spring. In practice, the slats 15 are made of such width and lateral stiffness that, while they will yield indi- 110

ividually sufficient to compensate for localized loads, they will still be capable of substantially maintaining their longitudinal straightness and so prevent the mattress or bedding from falling through or being pinched between the slats. Other advantages, in appearance, efficiency, and ease and economy in manufacture will be apparent to those skilled in the art.

10 The scope of the invention is defined in the appended claim, which is not necessarily limited by the described details of construction.

I claim—

15 In a bed spring construction, the combination of a rigid frame provided with a pair of opposed cross members at the ends there-

of, a transverse series of longitudinally disposed, spaced apart, thin, flexible slats, each provided with a plurality of spaced-apart 20 pairs of perforations, the perforations of each pair being spaced apart and located in a line extending transversely across the slat, means including a helical at one end of each slat for connecting same between 25 said cross members, and a plurality of transverse rows of individual helicals connected between adjacent slats for substantially preventing lateral separation of said slats, each of said helicals being closely coiled and provided with hooked extremities engaging respectively in adjacent perforations of adjacent slats. 30

DON CARLOS TRAVIS.
